US0D1045807S

(12) **United States Design Patent** (10) **Patent No.:** **US D1,045,807 S**
(45) **Date of Patent:** **** Oct. 8, 2024**

(54) **CABLE MANAGER**

(71) Applicant: **Shenzhen Yangwu Technology Co., Ltd.**, Shenzhen (CN)

(72) Inventor: **An Wu**, Shenzhen (CN)

(73) Assignee: **Shenzhen Yangwu Technology Co., Ltd.**, Shenzhen (CN)

(**) Term: **15 Years**

(21) Appl. No.: **29/946,854**

(22) Filed: **Jun. 12, 2024**

(51) LOC (14) Cl. **08-08**

(52) U.S. Cl.

USPC **D8/396**
